UNITED STATES PATENT OFFICE.

BENJAMIN F. MARTIEN, OF ASHLAND, OHIO.

DESIGN FOR A CHAFFER OR SIEVE SLAT.

SPECIFICATION forming part of Design No. 33,104, dated August 21, 1900.

Application filed July 18, 1900. Serial No. 24,114. Term of patent 14 years.

To all whom it may concern:

Be it known that I, BENJAMIN F. MARTIEN, a citizen of the United States, residing at Ashland, in the county of Ashland and State of Ohio, have invented and produced a new and original Design for a Chaffer or Sieve Slat, of which the following is a specification, reference being had to the accompanying drawings, forming part thereof.

10 Figure 1 is a perspective view of a chaffer or sieve slat, showing my new design. Fig. 2 is an end view of Fig. 1 in elevation.

As shown by the drawings, the leading or characteristic feature of my design consists 15 in a body portion having angular corrugations and a rod or bar engaging and intercepting the ribs of the corrugations on one side.

20 A represents the parallel ribs on one side of the slat, and B the parallel ribs on the opposite side. Between the ribs A are the grooves C,

and between the ribs B are the grooves or concavities D. The straight bar or rod E lies in contact with and intersects the convex surfaces of the ribs B on one side and projects beyond the body of the slat at the ends. The 25 bar or rod is not centrally disposed, but nearer one edge than the other. In the grooves or concavities C are a series of projections F, located adjacent the bar or rod. The general shape and configuration of the slat is clearly 30 indicated by the drawings.

Having described my invention, what I claim as new, and desire to secure by Letters Patent, is—

The design for a chaffer or sieve slat, as 35 herein shown and described.

BENJAMIN F. MARTIEN.
